H. O. STEPHENS

HEAT RADIATOR

Filed Jan. 28, 1926

Fig. 2.

Inventor:
Howard O. Stephens,
by *Alvanda S. Jones*
His Attorney.

UNITED STATES PATENT OFFICE.

HOWARD O. STEPHENS, OF PITTSFIELD, MASSACHUSETTS, ASSIGNOR TO GENERAL ELECTRIC COMPANY, A CORPORATION OF NEW YORK.

HEAT RADIATOR.

Application filed January 28, 1926. Serial No. 84,475.

My invention relates to heat radiators and more particularly to radiators adapted to be connected to the casing of oil-immersed electrical apparatus such as a transformer to increase the rate of dissipation of the heat generated in the apparatus while in operation. The general object of the invention is to provide an improved arrangement for securing the upper and lower ends of a heat radiator to an electrical apparatus casing. Another object of the invention is to arrange a heat radiator having top and bottom headers connected by heat radiating tubes in such manner that the headers will not impede the natural upward flow of convection currents of cooling air along the tubes.

Other objects and advantages will appear from the following description of one embodiment of the invention taken in connection with the accompanying drawing in which Fig. 1 shows one side of a transformer casing provided with a heat radiator constructed in accordance with the invention, Fig. 2 is a face view of the upper end of the radiator shown in Fig. 1 and Fig. 3 is a detail sectional view on the line 3—3 of Fig. 2.

Like reference characters indicate similar parts in the different views of the drawing.

The particular form of radiator shown in the drawing includes a top header 10 and a bottom header 11 connected by a plurality of heat radiating tubes 12. Each of the headers 10 and 11 is formed with two opposite metal walls 13 and 14 spaced a short distance apart by a metal strip 15 joining their edge portions, the joints being oil tight and preferably welded. The flat headers so formed are disposed vertically and are connected by the heat radiating tubes 12 which are offset from the vertical plane of the headers and have their upper and lower ends curved in to connect with the headers through the outer vertical walls 14 of the headers to which the ends of the tubes 12 are welded. The tubes may be flattened, if desired, as shown in the drawing.

The radiator is secured to and supported by a pair of short flanged tubes 16 welded into the wall of the transformer casing 17. A reinforcing plate 18 welded to the wall 13 of each header fits against the outer face of the flange of one of the flanged tubes 16, the headers communicating with the transformer casing 17 through openings in the walls 13, the reinforcing plates 18 and the flanged

tubes 16. The reinforcing plates 18 with their headers 10 and 11 are secured to the flanges of the flanged tubes 16 by bolts 19 which are surrounded by tubes 20 to seal them from the cooling liquid in the headers, the two ends of each tube 20 being welded to the reinforcing plate 18 and the wall 14 of the header. Shoulders around the bolt holes in the reinforcing plates 18 receive the ends of the tubes 20 and relieve the welded joints of all strain when the bolts are tightened.

The flat vertically disposed form of header which is provided by the present invention not only avoids interference with ascending convection currents of cooling air along the tubes 12 but also permits the bolts 19 which secure the headers in place on the flanged tube 16 to extend through without undue length to the outer walls of the headers. The outer walls 14 of the headers to which the radiating tubes 12 are attached are thus directly and strongly supported so that the headers themselves are largely relieved of strain due to the weight of the tubes 12 and the cooling liquid which they contain.

Having described a particular embodiment of the invention, it is to be understood that this is merely illustrative and that various modifications may be made within the scope of the invention as pointed out in the appended claims.

What I claim as new and desire to secure by Letters Patent of the United States is:

1. The combination with an electrical apparatus casing of a heat radiator comprising a top header and a bottom header, said headers being secured to the side wall of said casing, each of said headers having a substantially vertically disposed wall, and a plurality of heat radiating tubes offset from the plane of said vertically disposed walls, the ends of said tubes being curved in and secured to said walls, whereby ascending currents of cooling air along the tubes are not impeded by said headers.

2. The combination with an electrical apparatus casing of a heat radiator comprising a top header and a bottom header, each of said headers having opposite substantially vertically disposed walls, means for securing said headers to the side walls of said casing, the securing means for each header extending through both of its said walls, and a plurality of heat radiating tubes connecting said headers through their outer walls and

offset from the plane thereof, whereby ascending currents of cooling air along the tubes are not impeded by said headers.

3. The combination with an electrical apparatus casing of a heat radiator comprising a top header and a bottom header, each of said headers having opposite substantially vertically disposed walls, tubes extending through said headers and sealed to their opposite walls, means extending through said

tubes for securing said headers to the side wall of said casing, and a plurality of heat radiating tubes connecting said headers through their outer walls and offset from the plane thereof, whereby ascending currents of cooling air along the tubes are not impeded by the headers.

In witness whereof, I have hereunto set my hand this 22nd day of Jan., 1926.

HOWARD O. STEPHENS.
